UNITED STATES PATENT OFFICE

2,631,762

PRESSURE ACTUATED FOUNTAIN
TOOTHBRUSH

Ludwig F. Perwas, New York, N. Y.

Application June 6, 1945, Serial No. 597,749

1 Claim. (Cl. 222—402)

1

This invention relates to fountain tooth brushes of the type having a reservoir in the handle in which a dentifrice in the reservoir is fed to the bristles in the head of the brush as desired, and in particular a brush having a handle oval shape in cross section to provide space for two juxtaposed pumping cylinders with one adapted to provide pressure in the reservoir to feed the dentifrice, and the other adapted to create suction therein to draw dentifrice into the reservoir for refilling.

The purpose of this invention is to provide a fountain tooth brush in which a dentifrice contained therein is fed by air pressure to the bristles of the head and in which means is provided for readily refilling the brush.

Fountain tooth brushes are not generally accepted by the trade because they are usually too bulky and difficult to refill. With this thought in mind this invention contemplates a tooth brush having an offset head with a handle oval shape in cross section, to facilitate gripping and also to provide sufficient area for oppositely operating pumping elements for forcing dentifrice therefrom and replenishing dentifrice therein.

The object of the invention is to provide a simple, efficient, and positively operating fountain tooth brush wherein the elements are comparatively small so that it may be carried as a fountain pen.

With these and other objects in view the invention embodies an elongated substantially hollow handle, oval shape in cross section, having a reservoir therein and having a cap for enclosing a brush head at one end and a closure at the other, wherein a brush head is removably attached to an offset nipple at one end of the handle and manually actuated pressure and suction cylinders are provided at the opposite end.

Other features and advantages of the invention will appear from the following description taken in connection with the drawings, wherein:

Figure 1 is a longitudinal section through the fountain brush showing the brush head on the offset nipple and the pressure and suction cylinders with the intermediate portion of the handle broken away.

Figure 2 is also a longitudinal section through the fountain brush taken on line 2—2 of Figure 1, with the intermediate portion of the handle broken away.

Figure 3 is a cross section through the handle on line 3—3 of Figure 1.

Figure 4 is a similar section through the handle

2

taken on line 4—4 of Figure 1, showing the relative positions of the pressure and suction cylinders.

Figure 5 is also a section through the handle taken on line 5—5 of Figure 1 showing a spring clip for holding the closure to the handle.

Figure 6 is a detail showing a section through the closure and adjoining end of the handle illustrating the mounting of the spring clip thereon.

Figure 7 is a cross section taken on line 7—7 of Figure 2 showing the brush head mounting at the end of the nipple.

Figure 8 is a similar section on line 8—8 of Figure 2.

Figure 9 is an edge view of the nut shown in Figure 8.

Figure 10 is a detail showing a needle valve element of a check valve in the brush head.

Figure 11 is a detail showing a longitudinal section through the pressure cylinder illustrating the relative positions of the valves therein.

Figure 12 is a similar section through the suction or vacuum cylinder.

Figure 13 is a cross section through the connecting rods of the cylinders taken on line 13—13 of Figure 12.

Figure 14 is a fragmentary sectional view showing the rounded edges and crevices of the knurled surface of the nut shown in Figures 8 and 9.

Referring now to the drawings wherein like reference characters indicate corresponding parts the fountain tooth brush of this invention includes a brush head 1 having tufts of bristles 2 with a channel 3 extending into the inner end and provided with an outlet opening 4. In the channel 3 is a valve chamber 5 and a valve stem 6 with a slotted head 7 is slidably mounted therein with the pointed end of the valve stem held

by a spring 8 against a seat 9 in the end of the channel. The end of the channel 3 in the brush head is provided with internal threads 10 and with a washer 11 against the end 12 thereof the head is threaded on an offset nipple 13 at the end of the handle. The nipple is provided with a lock nut 14 having wrench receiving notches 14a therein by which the lock nut may be adjusted to secure the brush head in operative positions.

A conical shaped section with an opening 15 therein is provided adjacent the brush head and the offset nipple 13 on which the brush head is carried extends therefrom. Extending from the section having the opening 15 therein is the oval

55

shaped handle 17 which is connected thereto by a sealed joint 18 and the handle is provided with a reservoir 19 for holding a dentifrice. The end of the handle is provided with transversely positioned openings 20 which are formed in inwardly extending bosses 21, and springs 22 are provided in the openings which urge latch elements 23 outward. The latch elements are retained by washers 24 which permit the outer ends of the latch elements to snap into indentations 25 in a cap 26 that provides an enclosure for the brush head.

The cap 26 is also oval shape in cross section and the outer end is provided with a pocket clip 27 and has ventilating openings 28 therethrough.

The handle 17 is formed of a tubular casing, oval shape in cross section, and at the outer end 29 is a pumping section 30 having juxtaposed cylinders 31 and 32 therein, one of which is adapted to build up air pressure in the reservoir 19, and the other being adapted to withdraw air to create suction therein. The cylinders are separated by a partition 33 and the cylinder 31 has an outlet opening 34 whereas the cylinder 32 has an inlet opening 35, the said outlet and inlet openings providing communicating means between the cylinders and storage chamber. The opening 34 is provided with a ball check valve 36 that is opened by suction in the cylinder 31 to permit the air to be drawn from the reservoir, and the opening 35 is provided with an oppositely positioned ball check valve 37 that permits air to be pumped into the reservoir whereby pressure is created in the reservoir. A piston 38 is provided in the cylinder 31, and a similar piston 39 is provided in the cylinder 32, and it will be noted that the piston 38 is provided with a ball check valve 40 that is positioned to close an opening through the piston as the piston moves outward, and the piston 39 is provided with an oppositely positioned ball check valve 41 that is positioned to close as the piston travels inward to create pressure in the reservoir, and open as the piston is moved outward.

Each of the pistons is provided with a piston rod 42 having tubular connecting rods 43 threaded internally extending through the outer ends of the cylinders, and actuating rods 44 are threaded in the connecting rods. The outer portions of the connecting rods 43 are provided with air passages 45 providing communicating means with the interior thereof. On the outer ends of the actuating rods 44 are knurled nuts 46 having threaded shanks 47 adapted to be screwed into internally threaded bosses 48 of the cylinder heads 49. When it is desired to actuate either of the pumps the nut 46 thereof is unscrewed from the boss of the cylinder head and then the rod 44 is unscrewed from the connecting rod so that the knurled nut extends outward beyond the end of the casing to facilitate gripping by the thumb and forefinger so that the piston may be readily actuated.

As shown in Figures 1, 5, and 6, the cylinder head 49 is provided with a projection 50 having arcuate side surfaces with a narrow neck 51, and spring arms 52 of a U-shaped clip 53 are adapted to snap over the projection. The clip 53 is provided with outwardly extending arms 54 which are pivoted at the point 55 through a pin 56 in a slot 57 of a bracket 58 in a closure 59, and with the arms of the clip 53 withdrawn from the projection 50 the closure may be removed to facilitate operation of the pistons in the cylinders.

With the elements arranged and assembled as 75

described the cap and closure may be removed from the casing and by pumping the cylinder 32 air may be pumped into the reservoir to build up pressure therein so that dentifrice in the reservoir will be forced by the air pressure into the bristles of the brush head; and after the dentifrice is depleted the piston in the cylinder 31 may be actuated to withdraw air from the reservoir thereby creating suction therein so that with the brush head removed and the end of the nipple 13 connected to a dentifrice container the dentifrice will be drawn into the reservoir. The oppositely positioned valves 36 and 37 in the inner ends of the cylinders may be of any suitable type, however, in the design shown they are formed with balls held in the openings 34 and 35 by retainers 60 as shown in Figures 11 and 12.

A valve 6 is also provided in the channel 3 of the brush head to prevent moisture and the like entering the reservoir through the channel.

It will be understood that modifications may be made in the design and arrangement of the parts without departing from the spirit of the invention.

I claim:

In a fountain tooth brush, the combination which comprises a tubular handle, oval-shape in cross section, with a pumping section in one end and a dentifrice opening in the opposite end and having a pair of spaced parallel cylinders in the said pumping section, a transversely disposed partition positioned in the handle providing heads in the ends of the said cylinders, pistons having tubular rods extended from one of the sides thereof in the cylinders with said rods extended through the heads of the cylinders, thumb nuts on the outer ends of the piston rods and threaded in the said cylinder heads, said cylinders having passages through the inner ends thereof providing communicating means between the cylinders and interior of the said handle, check valves in said pistons, check valves in the passages in the inner ends of the cylinders, the valves in the pistons and inner end of one cylinder being positioned oppositely to the valves in the piston and inner end of the other cylinder whereby upon outward movement of the piston of one cylinder fluid is drawn into the interior of the handle through said dentifrice opening and upon inward movement of the piston of the other cylinder air is forced into the handle to feed dentifrice through said dentifrice opening.

LUDWIG F. PERWAS.
